G. ROBESON

INSECT DESTROYER

Filed Aug. 2, 1927.

Inventor

George Robeson

Lucy, Lucy, Attorney.

UNITED STATES PATENT OFFICE.

GEORGEAN ROBESON, OF WASHTA, IOWA.

INSECT DESTROYER.

Application filed August 2, 1927. Serial No. 210,123.

This invention relates to exterminators for winged insects, such as the ordinary house fly, and provides an article for killing the insect by means of a blow, and which is durable, effective and capable of being cheaply manufactured and supplied to the user at a nominal cost.

While the drawing illustrates a preferred embodiment of the invention, it is to be understood that in adapting the means to meet specific needs and requirements, the design may be varied and such other changes in the minor details of construction may be resorted to within the scope of the invention as claimed, without departing from the spirit thereof.

For a full understanding of the invention and the merits thereof, reference is to be had to the following description and the drawing hereto attached, in which,—

Figure 1 is a plan view of a fly killer embodying the invention, an intermediate portion of the handle being broken away.

Figure 2 is a longitudinal sectional view on the line 2—2 of Figure 1.

Figure 3 is a transverse sectional view on the line 3—3 of Figure 1.

Corresponding and like parts are referred to in the following description and designated in the several views of the drawings by like reference characters.

The device comprises a handle 1 and a striking member 2. In the preferable construction the handle 1 is formed of a length of stout wire which is folded upon itself and shaped at the end to which the member 2 is attached to provide a head 3 of approximately triangular form, the sides of which are inwardly curved, as indicated most clearly in Figure 1.

The head 3 coincides with the width of the striking member 2.

The striking member 2 is formed of a strip of wire fabric, such as generally used for fly screens. This strip is doubled upon itself and attached at one end to the triangular

head 3 of the handle. Preliminary to the doubling of the wire fabric strip upon itself its marginal edge portions are folded, as indicated at 4, to prevent raw edges, and to present a finished appearance, as well as to reinforce the side portions of the member. After the marginal edge portions of the strip have been folded the strip is doubled upon itself with the folded edge portions comprised between the folded parts of the strip, as indicated most clearly in Figure 3 of the drawings. The triangular head portion 3 of the handle is placed upon an end portion of the striking member 2 and the corner portions of the member are folded over opposite sides of the head 3, as indicated at 5. A wire 6 secures the folded corner portions 5 of the striking member and this wire also secures the member 2 to the head 3, by passing around a portion of said head and through and about meshed portions of the striking member. The wire 6 resists wear and insures a lasting connection between the striking member 2 and the head portion 3 of the handle, thereby resulting in the formation of a durable article.

Having thus described the invention, I claim:

A fly killer comprising a handle having a triangular shaped head, a striking member formed of a strip of wire fabric having marginal edge portions folded and the strip doubled upon itself with the folded edge portions between the folded parts of the strip, the striking member thus formed having an end portion placed against a side of the triangular shaped head with opposite corner portions folded over opposite sides of the head, and a wire securing the folded corner portions of the member and passing about the forward portion of the head and through and about meshed portions of the member to secure the latter to the triangular shaped head.

In testimony whereof I affix my signature.

GEORGEAN ROBESON. [L.s.]
